A CORPORATION OF PENNSYLVANIA

WINDOW LATCHING DEVICE

Application filed June 5, 1928. Serial No. 283,005.

This invention relates to latching devices for windows, more particularly to latching devices useful with pivoted or casement windows.

5 In latching devices heretofore designed for windows of the specific kind referred to, operation was effected by actuating members fulcrumed to swing in a plane parallel to the sashes. The manipulation of the 10 sashes under this condition of operation was more or less awkward and often required considerable physical exertion to latch and unlatch them, particularly with regard to 15 assurance of weather tightness in closed position.

Our invention is in part directed toward overcoming the indicated difficulty, which desideratum we attain through provision of a novel latching device wherein the actuating 20 member is swingable in the direction of sash movement, or in other words, perpendicularly to the plane of the sash.

In connection with a latching device embodying the above noted attribute, we further 25 aim to secure the advantages accruing to simplified construction and operation.

Still further objects and attendant advantages will be manifest from the detailed 30 description hereinafter when taken in connection with the drawings, whereof Fig. I shows a cross sectional view of a pivoted or casement window equipped with our improved latching device.

Fig. II is a perspective view of the device 35 with fragments of the meeting rails of the window frame and sash to which its component parts are secured; and,

Fig. III is an end view of the locking device.

40 As herein depicted, the device comprises a bracket member 10 adapted to be secured by screws or other convenient fastening means 11 to the inside of the swinging rail R of the pivoted or casement window sash S, which, as shown in Fig. I, is hinged at H to the stationary frame F. The bracket member 10 has spaced lateral projections 12, 13 with aligned openings 14, 15 to guide a sliding latch bolt 16, the projection 13 being 45 extended somewhat beyond its companion 50 55 60 65 70 75 80 85 90 95 100 12 to afford attachment for a stud 17 whereof the axis extends parallel to the bolt 16, and whereon is fulcrumed an actuating member having the form of a handle 18. From the fulcrum boss 19 of this actuating member 18 extends a sectoral wing 20 that provides a spiral cam edge 21 for engaging a transverse notch 22 in the outer side of the bolt 16, said wing 20 having oppositely projecting end lugs 23, 24 that co-operate with the bolt 16 to limit up and down swinging movement of the handle 18. The forward end of the latch bolt 16 is slightly beveled, as at 25, for wedge action with a counter-beveled "keeper" 26 secured to that jamb rail J of the frame F against which the swinging rail R of the pivoted sash S closes, all as clearly shown in Figs. I and II.

With the described arrangement it will be apparent that as the actuating handle 18 is lifted, the spiraled cam wing 20 causes retraction of the latch bolt 16 into the bracket 10 until the keeper 26 is entirely cleared, whereupon the sash S can be swung outward to open position. Locking of the sash S is effected conversely, that is to say: through depression of the actuating handle 18, such movement of the latter being attended by projection of the latch bolt 16 relative to the bracket 10 through reverse influence of the wing cam 21. In this connection it is to be particularly noted that by virtue of the wedge action between the bevel 25 of the bolt 16 and the counter bevel of the keeper 26, the sash S is securely clamped in closed position with the rail R contacting effectively with the jamb rail J as required for weather tightness. It is to be further remarked that the operating movement of the actuating member 18 is a natural one for both latching and unlatching the window sash S. In other words: the operative motion of the member 18 follows the direction of sash movement during opening and closing rather than being at right angles thereto as was ordinarily the case with heretofore available latching devices for pivoted windows, so that the sash S is readily latched or unlatched without entailing undue physical exertion. The handle 18 can, of course, be

given any desired configuration in keeping with the design or architecture of the window wherewith it is to be used, it being herein exemplified as rounded somewhat and directed away from the sash edge for convenience of grasping and preclusion of the possibility of injury to the hand in manipulating the window.

Having thus described our invention, we claim:

- 10 1. A latching device for pivoted windows comprising a bracket embodying spaced lateral projections of differing size, a latch bolt slidingly guided by said bracket projections, and an actuating member fulcrumed to the larger of said projections and adapted to follow the direction of sash movement, said actuating member embodying a spiral cam co-operative with the latch bolt.
- 15 2. A latching device for pivoted windows comprising a bracket member with unequal lateral projections and adapted for attachment to the side rail of the movable window sash, a latch bolt slidingly guided by said bracket projections, an actuator member fulcrumed to the larger of said bracket projections and adapted to swing in the direction of sash movement, said actuator member embodying a sectoral wing with a spiral cam edge engaging a transverse notch in the slide bolt, and movement-limiting stops at the termini of said cam edge.
- 20 3. A latching device for pivoted windows comprising a bracket member with unequal spaced lateral projections for attachment to the side rail of the window sash, a latch bolt slidingly guided by said bracket projections, an actuator member fulcrumed to the larger of said bracket projections and adapted to swing in the direction of sash movement, said actuator member embodying a sectoral wing with a spiral cam edge engaging a transverse notch in the latch bolt, and oppositely projecting end lugs for co-operation with the bolt in limiting movement of the actuator member.
- 25 4. As an article of manufacture an actuator for latching devices, of the type described, embodying a boss having a lateral manipulator member and an integral sectoral wing about said boss with a spiral cam edge terminating in stop projections.

In testimony whereof, we have hereunto signed our names, at Philadelphia, Pennsylvania, this 31st day of May, 1928.

JOSEPH H. SHEARD.
HARRY S. GETTY.
